R. E. SANDY

ADJUSTABLE MEASURE

Filed March 3, 1926

Fig. 1.

Fig. 2.

Inventor
R. E. Sandy,

By Clarence O'Brien

Attorney

UNITED STATES PATENT OFFICE.

RICHARD E. SANDY, OF CLOVERDALE, INDIANA.

ADJUSTABLE MEASURE.

Application filed March 3, 1926. Serial No. 91,981.

The present invention relates to improvements in measuring devices and more particularly to the type of measures wherein a container is provided for measuring various commodities in bulk.

One of the important objects of the present invention is to provide a measuring device which is adjustable to various sizes, thus obviating the necessity of having to employ a number of independent measures of different sizes.

A still further object is to provide an adjustable measure wherein the same may be readily and easily adjusted to the desired size or capacity, the same being very simple in construction, inexpensive, strong, and durable, and further well adapted to the purpose for which it is designed.

Other objects and advantages of this invention will become apparent from the following description taken in connection with the accompanying drawing:

In the accompanying drawing forming a part of this application, and in which like numerals designate like parts throughout the several views:

Figure 1 is a side elevation of my improved adjustable measure with parts shown in section so as to more clearly illustrate the adjustable bottom forming a part of the measure, and

Figure 2 is a sectional view taken approximately on line 2—2 of Figure 1 looking in the direction of the arrows.

In the drawing, wherein for the purpose of illustration is shown the preferred embodiment of my invention, the numeral 1 designates generally my improved adjustable measure, the same comprising the corrugated cylinder 2 which is open at its respective ends, the corrugations being arranged transversely and extending from the tops to the bottom of the cylinder.

Forming a part of the measuring receptacle is the adjustable bottom designated by the numeral 3, the same comprising a disc which is of such a diameter as to permit the same to be free to move vertically within the cylinder as will be presently described.

Cooperating with the bottom 3 are the opposed holders or supporting members 4 and 5 respectively. Each of said members is formed of an elongated strand of wire which is bent in the manner clearly shown in Fig-

ure 2 to provide a relatively large jaw 6 which is adapted for engagement with the corrugations formed in the cylinder 2, it being understood of course that the supporting members 4 and 5 are disposed on the underside of the bottom 3.

The free ends of the strand of wire forming each of said holders are disposed laterally in parallel spaced relation as indicated at 7 and the intermediate portion of the laterally extending portions 7 are disposed downwardly as illustrated at 8 to provide opposed finger grips, and the end portions of the wires are disposed inwardly as illustrated at 9. A thumb screw 10 extends between the parallel spaced ends of the laterally extending portions 7 and is threaded into the bottom 3 so as to provide a means for attaching the supporting members 4 and 5 to the under sides of the disc forming the bottom 3. However, it is to be understood that these thumb screws 10 will not interfere with the sliding movement of the opposed holders.

An expandible coil spring 11 is disposed over the inner opposed ends 9 of the holders 4 and 5, and the ends of this coil spring engage suitable stop pins 12 which extend transversely through the end portions of the wires forming the holders 4 and 5. The spring 11 normally exerts an outward pressure on the opposed members 4 and 5 so as to hold the jaws 6 of said members in the desired corrugations so that the bottom 3 will be secured in its properly adjusted position.

In order to adjust the sides of the receptacle, so that a predetermined measure may be obtained, the jaws of the holders 4 and 5 are disengaged from the corrugation in which the same are disposed, and this is accomplished by engaging the finger grips 8 of the respective holders and moving the same inwardly toward each other against the tension of the coil spring 11. When the jaws are out of engagement with the corrugations, and are disposed within the confines of the disc 3, the latter may be moved upwardly or downwardly within the cylinder 2 until the proper corrugation has been reached, and by releasing the finger grips 8 the coil spring 11 will automatically move the jaws into an operative position, thus holding the bottom in its newly moved position.

In this manner, a single measuring receptacle may be employed and may be readily and easily adjusted to various sizes, thus obviating the necessity of having to provide measuring receptacles of different sizes or capacities.

A suitable handle such as is shown at 13 is attached to the side of the cylinder 2 and facilitates the handling thereof.

10 The purpose of providing the adjustable bottom is to enable the measuring receptacle to be used in connection with measuring dry material which vary in bolts per pound. By first weighing the material, the user of 15 the device can adjust the bottom to that particular weight and thereafter the measuring receptacle may be used and will measure accurately the material which is dispensed.

While I have shown the preferred embodiment of my invention, it is to be understood that minor changes in the size, shape and arrangement of parts may be resorted to without departing from the spirit of the invention and the scope of the appended 25 claims.

Having thus described the invention, what I claim as new and desire to secure by Letters Patent is:—

1. An adjustable measuring receptacle 30 comprising a corrugated cylinder open at its respective ends, a bottom forming member slideable within the cylinder, means for holding said bottom forming member in any adjusted position in the cylinder, said means 35 comprising a pair of opposed jaws slidably mounted on the under side of said bottom forming member, said jaws being adapted

to be disposed within one of said corrugations.

2. An adjustable measuring receptacle 40 comprising a cylinder which is open at its top and bottom, said cylinder being corrugated transversely for its entire length, a bottom forming member adapted for slideable movement within the cylinder, a pair 45 of opposed jaws slideable on the under side of the bottom forming member and adapted to engage one of said transversely disposed corrugations for holding the bottom forming member in any desired adjusted position, and resilient means associated with said opposed jaw members for normally maintaining the same in an operative position.

3. An adjustable measuring receptacle 50 comprising a corrugated cylinder open at its respective ends, a bottom forming member adapted for slideable movement within the cylinder, means for holding said bottom forming member in any adjusted position in the cylinder, said means comprising a pair 55 of opposed jaws, each of which is formed from a strand of wire the free ends thereof being disposed laterally in parallel spaced relation adjacent the under side of said bottom forming member, the intermediate 60 portions of said laterally extending portions being disposed downwardly to provide opposed finger grips, and resilient means associated with the end portions of the laterally extending portions for normally maintaining the jaw members in one of said corrugations.

In testimony whereof I affix my signature.
RICHARD E. SANDY.
